TRIMMING MACHINE

Jacob S. Kamborian, Newton, Mass., assignor to
 United Shoe Machinery Corporation, Paterson,
 N. J., a corporation of New Jersey

Application February 24, 1938, Serial No. 192,381

8 Claims. (Cl. 12—83.5)

This invention relates to trimming machines and more particularly to machines adapted to sever surplus material from the bottoms of lasted shoes.

5 In trimming the bottoms of lasted shoes an operator usually feeds the shoe manually past a trimming cutter. It is essential in this operation that the operator be able to control the widthwise location and the depth of the cut at all portions of the shoe bottom. When operating upon 10 shoes in which the overlasted portion of the upper is secured in contact with the surface of the insole as, for example, in cement lasted shoes, manual control of the cut by the operator is especially difficult because the material to be 15 severed is located in a flat position and there is no upstanding rib or other means on the shoe bottom to assist the operator in guiding the shoe. Moreover, many trimming machines are 20 of the type which requires advancing the shoe manually past the cutter once for trimming one side of the shoe and again for trimming the opposite side, the trimming cut starting at about the tip line at each side of the shoe and usually terminating at the ball line. In such cases it is 25 necessary that the operator, in advancing the shoe past the cutter, be able to guide the shoe properly and to control the location and depth of the trimming cut at each side thereof. 30 Accordingly, an object of the present invention is to provide improved means for guiding a shoe manually past a trimming cutter, to the end that the trimming will be uniform along both sides of the shoe with respect to the distance of the 35 cuts from the corresponding outlines of the shoe bottom and also with respect to the depth of the trimming cuts.

To the attainment of this object and in accordance with one feature, the invention provides, in 40 combination with a power operated cutter, a member arranged to serve as a depth or bottom gage for controlling the depth of the trimming cuts, and two abutments arranged to serve as side gages for engaging opposite sides of the shoe. 45 The side gages or abutments are located side by side or abreast of each other, and are spaced from each other sufficiently to permit a shoe to pass between them while engaging only one of the abutments. Moreover, the abutments are adapted 50 to be readily shifted widthwise or laterally of the path of movement of the shoe and are so arranged that each is moved into a position to clear the path of the shoe when the other is shifted into its operative or shoe engaging position. As illustrated herein, the member that serves as a bot-

tom gage is also arranged to support and shift the side gages or abutments in the manner described.

With the above and other objects and features in view, including also improved mechanism for automatically maintaining each abutment in its operative position relatively to the cutter, the invention will now be described in connection with the accompanying drawings and will thereafter be pointed out in the claims.

In the drawings,

Fig. 1 is a front elevation of the machine embodying the present invention with the base portion of the frame broken off;

Fig. 2 is a fragmentary sectional view taken on the line II—II in Fig. 1;

Fig. 3 is an enlarged front view partly in section showing the trimming cutter operating on a shoe bottom; and

Fig. 4 is an enlarged transverse section taken on the line IV—IV of Fig. 1.

The machine comprises an upstanding frame 10 having a laterally extending upper portion 12 at the end of which is formed a supporting block or head 14. Rotatably mounted in suitable bearings in the head 14 is a shaft 16 which is rotated by a pulley 18 fastened to the inner end of the shaft, as viewed in Fig. 1. Fixed to the forward end of the shaft by a set screw 20 is a hub member 22 closed at its front end and carrying thereon a forwardly extending pin 24 located eccentrically with respect to the axis of the shaft. The pin 24 passes through a slot 26 in the upper portion of a carrier member 28 mounted for oscillating movement on the forward end of a fixed shaft 30 the inner portion of which is supported in a block 32 (Fig. 4) fastened to the lower side of the head 14, the shaft being secured to the block by a nut 34.

The eccentric pin 24 carries thereon between a pair of roller bearings (not shown) a slide block 35 of usual construction which rides on adjustable gibbs 36 in the slot 26 and which, when the shaft 16 is rotated, causes the pin 24 to oscillate the carrier member 26 about the fixed shaft 30. The portion of the carrier member surrounding the shaft 30 likewise carries a roller bearing 37 (Fig. 4) for reducing friction between the moving parts, the roller bearing being secured within a cover 38 by a nut 39.

The lower end of the carrier member 28 has two downwardly projecting arms 40 extending away from each other at an angle of substantially 45° and having secured to their lower ends by screws 44 an arcuate trimming knife or cutter 42.

provided with a cutting edge 43. The cutting edge 43 of the cutter, which is toward the operator as viewed in Figs. 1 and 3, is scalloped, as shown in Fig. 4, and the outer surface of the cutter is 5 ground cylindrical, as indicated at 46 in Fig. 4, to facilitate the cutting action of the cutter while permitting the cutting edge 43 to execute a scooped cut in a substantially flat plane without digging into the insole.

10 The upstanding portion of the frame 10 has secured by screws to its forward side a plate 50 provided with a vertical slot or guideway 52 in which is mounted for heightwise adjustment relatively to the plate a substantially horizontal block 15 54, the block being secured to the plate by a screw 56 passing through a slot 57 (Fig. 2) in the frame and plate 50.

The block 54 is provided with a horizontal groove 58 (Fig. 2) in which a bar 60 is arranged to 20 slide lengthwise and is maintained therein by a cover plate 62 affixed to the block. As viewed in Fig. 1, the left-hand portion 64 of the bar 60 extends across the shoe A and behind the cutter 42 and its lower surface, which is only slightly above 25 the level of the lowest point of the cutter, is arranged to be engaged by the upturned bottom of the shoe to control the depth of the cutting. Moreover, this portion of the bar is also utilized to carry two underslung side gages or abutments 30 66 spaced one from the other a distance slightly greater than the widest part of the widest shoe to be trimmed. Consequently any shoe may pass freely between them. The side gages are shown as circular rolls or disks and they are freely rotatable on pivot studs 68 by which they are mounted on the bottom of the horizontal bar. These pivot studs having eccentric screw shanks 70 and are secured to the bar by nuts 71 and are effective, when turned, to adjust the side gages 40 toward and from each other. When the bar 60 is shifted to the right, as in Fig. 1, the right-hand side gage 66 is retracted to clear the shoe while the left-hand side gage stands in its operative position, but when the bar 60 is shifted to 45 the left, it shifts the left-hand side gage so that it clears the path of the shoe and it simultaneously locates the right-hand side gage in an operative position.

Since the crossbar 60 has fixed limits of shifting 50 movement, the individual adjustment of the side gages or abutments 66 afforded by the eccentric studs 68 provides for regulating the width of the margins of upper material remaining after the surplus portions have been severed therefrom. As the parts are shown in Figs. 1 and 3, the left-hand abutment 66 is in a position to guide the shoe A past the cutter to permit the latter to operate on the left-hand marginal portion of the upper. After the cutter has trimmed this side 60 of the shoe, the left-hand abutment 66 may be shifted out of its operative position and the right-hand abutment shifted laterally of the path of the shoe into a position in which the right-hand side of the shoe may be placed against this abutment to permit the cutter to operate on the right-hand marginal portion of the shoe bottom.

The shifting of the side gages or abutments 66 laterally of the cutter is accomplished by a treadle 72 adjustably connected by a rod 74 to an 70 angle arm lever 76 pivoted to a lower portion of the frame 10 by a stud 78 and having an upwardly extending arm 80 which is pivotally connected to the bar 60 by a screw 82 passing through a slot in the end of said arm. In order 75 to limit the lateral movement of the bar 60 to

an amount that will shift each abutment 66 alternatively into and out of an operative position which is predetermined with respect to the cutter, the bar has a stop 84 secured to its upper side by a screw 86, the stop serving to limit shifting movement of the bar toward the right, as viewed in Fig. 1. The shifting movement of the bar in the opposite direction or toward the left is limited by contact of the arm 80 with the right-hand end of the supporting block 54. The construction is 10 such that the movement of the bar between these two stops shifts the abutments 66 respectively into or out of the desired operative positions relatively to the cutter 42.

It is desirable that each abutment should be 15 maintained against movement out of operative position during the trimming operation on the side of the shoe which the particular abutment is guiding past the cutter. Accordingly, there is provided on the lower side of the bar 60 a pair of indentations or notches 88 and 89 (Fig. 1) located in a predetermined spaced relation to each other. The block 62 is provided with a cylindrical boss 90 on its lower side in which is mounted a compression spring 92 retained in the boss by a screw 25 94 and acting against a pin 96 having a rounded end arranged to snap into one of the notches 88, 89 when either notch registers therewith. The location of the notches 88, 89 on the bar 60 is such that, when the left-hand notch 88 is 30 engaged by the spring pin 96, the left-hand abutment 66 will be in an operative position, as shown in Figs. 1 and 3. The pin 96 acts to maintain the bar and the abutment in an operative position until they are moved out of this position by manual operation of the treadle 72 by the operator to move the arm 80 against the end of the block 62 and thus to bring the right-hand notch 89 into registration with the pin 96, at which time the right-hand gage 66 will be located in its operative 40 position so that the right-hand margin of the shoe may be operated upon by the cutter.

As pointed out above, the machine is adapted particularly to sever surplus material from the overlasted marginal portion of an upper which 45 lies flat against the surface of the insole of the shoe as, for example, where the upper has been lasted to the insole by cement and has no upstanding portion which could be trimmed off without danger of damaging the insole. The 50 cutter 42 is arcuate in shape and executes a scooped cut in removing this surplus material from the inner margin of the upper. Moreover, as stated above, the cutter has a cylindrical outside surface at, and adjacent to, its cutting edge 55 which acts to prevent the cutter from digging into the insole. In order, however, that the operator may be able to control the depth of the trimming cut, it is necessary that the shoe be guided and controlled heightwise of the cutter 60 as well as widthwise thereof. In the present construction this is accomplished by arranging the lower side of the bar member 60 in a heightwise position which is slightly above the level of the lowest point of the cutting edge of the cutter. Accordingly, the bottom of the shoe may be rested against this lower side of the bar in controlling the heightwise position of the portion of the shoe bottom upon which the cutter is to operate. The 70 shiftable bar 60, therefore, not only carries the side gages or abutments 66 and locates them alternatively in their respective operative positions relatively to the cutter, but it also serves as a guide or bottom gage for controlling the 75

heightwise position of the shoe bottom during the trimming operation. It will be seen, moreover, that the bar 60, in conjunction with the abutments 66, provides means whereby any rolling or tipping movement of the shoe may be controlled as desired by the operator. In other words, the abutments 66 and the support or rest afforded by the bar 60 permit the operator to control at will the angle at which the shoe moves past the cutter and thereby to gage the location of the material trimmed from the shoe bottom as well as the depth of the trimming cut.

In using the illustrated machine the operator presents the shoe A to the cutter by placing the toe end of the shoe bottom against the lower side of the crossbar 60, and one side of the shoe against the proper side gage 66 then in its operative position. While moving the shoe toe foremost between the side gages or abutments he may raise or lower its heel end to regulate the depth of the cutting as controlled by the crossbar, to the end that the operating segment of the cutting edge 43 will be tangent to the insole, as shown in Figs. 3 and 4. After feeding the shoe to sever the surplus material from the margin at one side, he will remove the shoe, shift the side gages to locate the opposite gage in operative position and again feed the shoe toe foremost to sever the surplus material from the margin at the opposite side of the shoe. It is usually sufficient to extend such trimming to points a short distance rearwardly of the ball line.

Although the trimming problem with which the present invention is primarily concerned arises chiefly in shoes lasted with cement only, and having no rib or lip on the insole, the described machine is nevertheless capable of trimming surplus material that stands up from the insole, as in a shoe in which the lasting margin of the upper is side-lasting with cement and temporarily secured with staples to a rib or lip on the insole. In trimming a shoe of this type, the cutter will sever the rib or lip of the insole preferably below the staples while removing the surplus material of the upper, thereby leaving the bottom of the forepart virtually smooth and even to receive a filler and an outsole.

Having thus described my invention, what I claim as new and desire to secure by Letters Patent of the United States is:

1. A trimming machine having, in combination, a power operated cutter arranged to sever surplus material from the bottom of a lasted shoe moved past the cutter, a member arranged to be engaged by the shoe bottom for controlling the depth of the cut made by said cutter, and laterally shiftable gaging means movable to one position for guiding one side of the shoe with respect to the cutter and to another position for guiding the opposite side of the shoe with respect to the cutter.

2. A trimming machine comprising a power operated mechanism including a cutter arranged to sever surplus material on the bottom of a lasted shoe, a member arranged behind the cutter to be engaged by the shoe bottom to control the depth of cutting, two side gages spaced apart to enable the shoe bottom to pass freely between them while in contact with said cutter and said controlling member, and manually operable means arranged to shift said gages sidewise to locate one of them in an operative position and retract the other, and vice versa.

3. A trimming machine comprising the combination of elements set forth in claim 2, in which

the member that controls the depth of cutting is an element of said manually operable means and is utilized to support the side gages and shift them to and fro.

4. A trimming machine having, in combination, a power operated cutter arranged to sever surplus material from the overlasted marginal portion of a shoe upper, a member shiftable laterally of said cutter, a pair of abutments carried by said member and arranged respectively to guide opposite sides of the shoe past said cutter, means for controlling the depth of the cut formed by said cutter, and means for shifting said shiftable member laterally of the cutter into predetermined positions to locate said abutments alternatively in operative positions at opposite sides of said cutter.

5. A trimming machine having, in combination, a power operated cutter arranged to sever surplus material from the overlasted marginal portion of a shoe upper, a member shiftable laterally of said cutter, a pair of side gages carried by said member and arranged respectively to guide opposite sides of the shoe past said cutter, means for controlling the depth of the cut formed by said cutter, means for shifting said shiftable member laterally to locate the side gages alternatively in predetermined operative positions relative to said cutter, and means for maintaining each side gage in its operative position during the trimming operation on that side of the shoe.

6. A trimming machine having, in combination, a power operated cutter arranged to turn about an axis to sever surplus material from the overlasted marginal portion of a shoe upper, a manually shiftable member, a pair of abutments carried by said member and arranged to be engaged alternatively by opposite sides of the shoe and to guide the shoe past said cutter, means arranged to maintain said shiftable member in each of two positions to locate said abutments respectively in operative positions relatively to the cutter but at opposite sides thereof, and means arranged to be engaged by the bottom of the shoe to control the depth of the cut formed by said cutter.

7. A trimming machine having, in combination, a power operated cutter arranged to execute a draw cut to sever surplus material from an overlasted marginal portion of an upper lying on the insole of a lasted shoe, a manually shiftable member, a pair of rotatable abutments carried by said member and arranged to be engaged alternatively by opposite sides of the shoe to guide the shoe past said cutter, said abutments being spaced apart a distance greater than the widest part of the shoe, means arranged to maintain said shiftable member automatically in each of two positions to locate said abutments alternatively in operative positions at substantially equal distances from the operative point of the cutter but at opposite sides thereof, and means arranged to be engaged by the bottom of the shoe adjacent to said operative point whereby the depth of the cut may be controlled.

8. A trimming machine having, in combination, a power operated cutter arranged to oscillate about a fixed axis and having an arcuate cutting edge for executing a draw cut to sever surplus material from the inner portion of an overlasted upper secured against the insole of a shoe, a member shiftable laterally of said cutter in a plane located at one side of the path of said cutting edge and arranged to be engaged by the shoe bottom to control the depth of said cut, a pair of freely rotatable abutments carried by said member and spaced apart thereon a distance greater than the

widest part of a shoe, said abutments being arranged to be engaged respectively by opposite sides of the shoe to guide each side past the cutter, manually operated means for shifting said member into each of two positions laterally of the cutter to locate said abutments alternatively in

positions to be engaged by the shoe, means for positively limiting the lateral shifting movement of said member, and means for automatically retaining said member in either one of its two positions.

JACOB S. KAMBORIAN.
